US00D592174S

(12) **United States Design Patent**
Mo et al.

(10) **Patent No.:** **US D592,174 S**
(45) **Date of Patent:** **** May 12, 2009**

(54) **COMMUNICATION DEVICE**

(75) Inventors: **Jia-Jun Mo**, Beijing (CN); **Fu-Yuan Hsu**, Beijing (CN)

(73) Assignee: **Motorola, Inc.**, Schaumburg, IL (US)

(**) Term: **14 Years**

(21) Appl. No.: **29/327,903**

(22) Filed: **Nov. 14, 2008**

(51) **LOC (9) Cl.** **14-03**

(52) **U.S. Cl.** ..... **D14/138 AB**

(58) **Field of Classification Search** ..... D14/138 AB,
D14/496, 341-347; 455/575.3

See application file for complete search history.

(57) **CLAIM**

The ornamental design for a communication device, as shown.

DESCRIPTION

FIG. 1 is a perspective view of a first embodiment of an ornamental design for a communication device;

FIG. 2 is a rear view of the first embodiment thereof;

FIG. 3 is a front view of the first embodiment thereof;

FIG. 4 is a first side view of the first embodiment thereof;

FIG. 5 is a second side view of the first embodiment thereof;

FIG. 6 is a bottom view of the first embodiment thereof; and

FIG. 7 is a top view of the first embodiment thereof.

FIG. 8 is a perspective view of a second embodiment of an ornamental design for a communication device;

FIG. 9 is a rear view of the second embodiment thereof;

FIG. 10 is a front view of the second embodiment thereof;

FIG. 11 is a first side view of the second embodiment thereof;

FIG. 12 is a second side view of the second embodiment thereof;

FIG. 13 is a bottom view of the second embodiment thereof; and,

FIG. 14 is a top view of the second embodiment thereof.

The broken lines shown in FIGS. 1-7 that are immediately adjacent to the shaded areas and define unshaded regions, represent the bounds of the first embodiment, while all other broken lines are directed to environment and are for illustrative purposes only; the broken lines form no part of the first embodiment.
